CONTAINER CLOSURE

Forest C. Barber, Bartlesville, Okla.

Application May 25, 1939, Serial No. 275,606

7 Claims. (Cl. 266—39)

This application is a continuation-in-part of my copending application Serial No. 207,542, filed May 12, 1938. My present invention relates to closures for open mouthed vessels, particularly to closures for vessels which have mouths substantially in a vertical plane, and more particularly to closures for use in connection with various smelting operations where molten metals are to be retained in a vessel, especially a horizontal vessel, and hot and corrosive gases are not to be retained.

In the smelting of zinc ore to produce the metal in an uncombined form, zinc ore and coke in a finely divided or pulverized form are intimately mixed and heated together. A chemical reaction takes place involving these materials and zinc is released from chemical combination with other elements. The zinc can be obtained as a product of this reaction in a substantially pure metallic form except as it may be more or less contaminated by other metals which may be present as components of the ore.

In commercial practice this chemical reaction, or smelting, is often carried out in a relatively small retort, which is frequently a cylinder about one foot in diameter and about six feet long and closed at one end. This cylinder has walls about an inch thick which are composed of baked clay, or other ceramic material, which is quite resistant to high temperatures and the destructive action of hot corrosive materials, such as molten or vaporized metals. This retort is placed in a furnace with its long axis substantially horizontal, the closed end being within the furnace and the open end being at the edge of the furnace and substantially flush with the outer wall thereof. This outer, open end is preferably slightly lower than the inner, closed end so that any liquid material such as molten metal which may at any time be within the retort will tend to flow out of the retort and yet any solid material such as unreacted ore or coke, or cinders and the like, which remain after reaction, will not tend to slide out of the retort by the force of gravity.

As a result of the high temperatures which exist within this retort, the zinc or other metal produced by the smelting of the ore therein will be at or near its boiling point and therefore will have an appreciable vapor pressure and substantial amounts, if not all, of the zinc will exist in the vapor state. In order to be collected the metal vapor must be condensed, much as the vapor of any other material which it is desired to recover, and for this purpose a condenser is used in cooperation with the aforementioned re-

tort. This condenser is made of a temperature-resistant ceramic material which is similar to or the same as the material from which the retort is made. In one form, this condenser has the shape of a hollow, truncated cone about two and one-half feet long, with walls which are also about an inch thick. The base or larger end of this condenser has essentially the same dimensions as the open end of the aforementioned retort, against which it is fitted more or less snugly. The smaller end of this conical condenser is between about two and six inches in diameter. The condenser rests upon brackets or the like, with its axis also substantially horizontal, but with enough of an angle therefrom that the bottom portion of the smaller end is slightly lower than the bottom portion of the larger end. Free metal in a substantially molten state collects in this condenser, running into it from the retort and condensing from the gases and vapors which leave the retort and pass into and through the interior of the condenser toward the smaller end thereof.

It has heretofore been the practice of the art partially to close or dam the small end of this condenser with a handful, more or less, of dampened granular material such as cinders or the like, leaving a small hole or unclosed portion near the top part of the condenser through which pass gaseous reaction products of the smelting operation, somewhat cooled in the condenser and freed of substantially all of the metal vapors. This handful of material must of necessity be put in place by hand, and whenever it is desired to draw off the molten metal which has collected in the condenser, this dam must be removed completely. In doing this, the dam material and molten metal are raked or scraped into a ladle, the dam material floating on top of the metal and being removed from time to time as collection of metal from large numbers of individual retorts proceeds.

In my aforementioned copending application Serial No. 207,542, there is described a closure suitable for use in such a smelting operation, and which possesses many advantages over the prior art. Briefly, this closure includes a suitable cover comprised of inert insulating material, and provided with a suitable vent, with means for attaching this cover to a condenser such as has just been described, and with means for firmly holding the cover against the mouth of the condenser.

I have now invented a device, or closure, which is easily and quickly attached to the end of such a condenser, which will hold back the molten metal while allowing uncondensed vapors and

gases to escape, which may be easily and repeatedly opened and closed without undue effort, which is readily adjusted to remain open and to remain firmly closed, which is substantially immune to the corrosive and destructive action of high temperatures and molten metals, and which possesses other advantages over the prior art. This closure includes a cover comprising suitable thermal insulating material and which is so fashioned as to fit firmly against the smaller, open end of such a condenser and to hold the molten zinc in while, as will be described, still permitting the unwanted gases to escape; which is provided with means to be more fully hereinafter described which attaches the entire closure to the condenser; which is attached to the said attaching means by arms from each side of said attaching means to each side of the cover which are so positioned as to control and guide the cover in such a manner that its own weight, and shape, aid in keeping it over and firmly pressed against the mouth of the condenser, and which aid in holding in molten metal which tends to escape from the condenser.

It is an object of my invention to provide a closure for an open-mouthed vessel which can be readily and quickly opened and closed.

Another object of this invention is to provide a closure which comprises or has incorporated with it a material suitable for thermal insulation and also suitable as a gasketing material.

A further object of my invention is to provide a closure for an elongated, horizontal, open-mouthed vessel which has its mouth substantially in a vertical plane and which comprises a cover which is held against this mouth in part, at least, by its own weight.

Further objects and advantages of my invention will be apparent to those skilled in the art from the accompanying disclosure and discussion.

Reference will now be made to the accompanying drawing which forms a part of this disclosure, and in which:

Fig. 1 presents a side plan view of the end of a zinc condenser, with one modification of my invention attached, and with the cover in a closed position.

Fig. 2 presents the same plan view as Fig. 1, but with the mouth of the vessel uncovered and with the cover in a raised position, sitting out of the way on the condenser body.

Fig. 3 presents a top plan view of the same modification of my invention, with the cover in a closed position.

Fig. 4 presents a front plan view of one modification of a cover, which is the same modification shown in the preceding figures.

Fig. 5 presents a front plan view of another modification of a cover.

The condenser body 10 is in a substantially horizontal position, and is supported as has been discussed, by means not shown. For the modification of my invention illustrated, the closure combination is attached to the condenser body 10 by a band 11 which encircles and firmly grips the condenser body 10, and which can be loosened and drawn tight by proper manipulation of the screw-bolt 12 which passes through a plain hole in the lug or ear 13 at one end of the band 11 and screws into a threaded hole in the lug or ear 14 at the other end of said band. Preferably, although not necessarily, the band comprises two halves which are hinged together opposite such connecting and adjusting means, such as with a hinge 9. The inside of the band 11 may be provided with a plurality of small, more or less

sharp, short projections which tend to dig into the clay condenser 10, thereby aiding the band 11 to be securely fastened thereto without slipping. Another modification by which such a band can be securely attached to the condenser body 5 involves the presence of a shallow, sunken ring formed in the condenser body in which the said band may fit. Other modifications will now be apparent to those skilled in the art.

A cover 15, of which a front plan view may be 10 substantially circular, as shown in Fig. 4 and of a size preferably slightly larger than the end of the condenser 10, fits firmly against the end of the condenser, as shown in Fig. 1. Attached on each side of this cover 15 are pivotal means such 15 as the projecting pins 16 and 16', having their axes on a common, horizontal line which is located well below the top of the cover 15, and is also above the center of gravity of the cover, so that when hanging freely from the pivotal means 20 it tends to hang in a substantially vertical plane, and with the bottom and top in the proper relationships.

The body of the cover 15 may be composed of molded ceramic material, or fire clay, similar 25 to that now used in making the condenser body 10. In such a case it may be surrounded and held by a band 17, to which are securely attached the pivotal means 16 and 16'.

When it is made of such molded ceramic material, it may be 30 molded and formed directly in the encircling band 17, which may then be a continuous band, as shown. When this cover is separately formed, it may be encircled by an adjustable band adapted to be readily attached and removed, and to grip 35 the cover firmly. As another modification, a suitable metallic framework may be provided, carrying such pivotal means 16 and 16', and the ceramic material of the cover may be molded around it, leaving the said pivotal means 40 protruding. It is desirable that the cover 15 be comprised of material suitable for withstanding the high temperatures and corrosive action of molten zinc, and such ceramic material as is used to make the condenser is inexpensive and fulfills 45 these qualifications. However the cover 15 may be made in a more mechanically durable manner, as by forming a cover blank of iron, or the like, and facing it on the side next to the condenser with a suitable inert thermal insulating material 50 such as asbestos, or the aforementioned fire clay, as will be readily appreciated, the necessary pivotal means being readily attachable to such a metal body. When the cover is so made as to cover the entire mouth, as in Fig. 4, it is to be 55 provided with a vent hole 24 in the upper portion, through which gases and vapors may escape. This vent hole should be unobstructed and sufficiently large so that it will not become clogged by any solid material which may be deposited 60 on its edges.

Each pivotal means or pin may have a collar, as shown, and, if necessary, pins 18 and 18' may be attached to and well below the collars, the functions of which will become evident herein- 65 after.

Attached to the band so as to be on each side of the condenser body are pivotal means such as the projecting pins 20 and 20', having their axes on a common horizontal line which is appre- 70 ciably higher than the line of the axes of pivotal means 16 and 16', when the cover 15 is in a closed position as shown in Fig. 1. These pins are preferably provided with collars, as shown.

Arms 22 and 22' connect and hold the cover to 75

the band 11. Each of these arms has a hole in each end through which pass the pins 16 and 20, and 16' and 20', respectively. The sidewise movements of these arms in the respective pivotal means is restricted on the one side by the collars provided on these means, and the pins shown may be provided with transverse holes through which cotter keys 23 and 23', and 29 and 29', can be passed, thus preventing the arms from coming off, and preferably with a washer between the cotter key and the arm. Other suitable and familiar means for accomplishing this result may be adapted, as will be readily appreciated. While, because of the structural relationships which exist, the arms 22 and 22' lie in the same plane, they will generally and preferably not be parallel as long as the condenser body 11 has a shape similar to that of a truncated cone, as shown and discussed, but will preferably be more or less parallel to the sides of the condenser, as shown. However, it will of course be preferable that the ends of these arms will be perpendicular to the pins, as shown.

One alternative modification, not shown, is to have the arms 22 and 22' constitute the two arms of an U-shaped member made of a rigid bar, with a circular cross section at pivotal points, the bottom of this U-shaped member passing in front of the cover 15, which is pivotally attached thereto by apertured or hooked forwardly projecting extensions from the encircling band 17 on either side of the cover 15, the bottom of the U-shaped member passing through the said apertures or hooks. The ends of such an U-shaped member may either be flattened and apertured to receive the pins 20 and 20', or they may be hooked around them, or alternately the band 11 may support apertured lugs in place of the projecting pins 20 and 20', and the ends of the U-shaped member may be bent to pass through such apertures and pivotally cooperate therewith as is readily appreciated. Other modifications may also be applied.

The advantages of this arrangement, and combination, will now become more apparent. With the band 11 firmly fixed on the condenser body 10 a suitable distance back of the mouth of the condenser, the cover 15 falls in front of the mouth and its own weight serves to fit it snugly and firmly against the edges of the end of the condenser which define this mouth. The position of the axes of the pivotal means 20 and 20' substantially above the axes of the pivotal means 16 and 16' not only contributes to this action, but also acts to enable the cover 15 to move away from the mouth when it is lifted, and also assures that the cover may be lifted entirely free of the mouth, and may be rested on top of the condenser, as shown in Fig. 2. When in this position, the projecting pins 18 and 18', if used, will meet the arms 22 and 22' to prevent the cover 15 from swinging back through these arms. The cover 15 may be provided with a projecting lug or handle 27, preferably at the top as shown, which is useful in taking hold of the cover and moving it away from the mouth or swinging it in place, especially in cooperation with some long handled instrument in the hands of an operator, as will be readily appreciated.

It will be possible, of course, for the pivotal means 20 and 20' to be higher than pivotal means 16 and 16' on the cover, when it is closed, and still be insufficiently high to permit the cover to be pushed up past the top part of the end of the condenser. Thus, when it is stated that the

pivotal means on the attachment means is substantially higher than the pivotal means on the cover, it is to be understood that the first said pivotal means is not only higher, but also is enough higher to obviate such difficulties. 5

Clamping of the band 11 may be readily accomplished with the cover 15 over the mouth, and in this manner the proper distance of the band back of the mouth is readily attained. However, even should the band be a little backward or forward of the optimum position, the cooperation of the apparatus is such that the cover 15 will fit firmly against the mouth. This will be particularly true if the cover is of such a size and shape as normally to project a little above and below 15 the top and bottom, respectively, of the mouth, and suitable provision for this is contemplated. When the circumstances warrant, this cover will preferably be somewhat elliptical rather than circular as shown in Fig. 4, with the long axis being 20 the vertical axis. The above mentioned cooperation of the apparatus to compensate for slight deviations from the optimum for the position of the band, or as it may be, of the length of the arms 22 and 22', is found to be of especial advantage when a sunken ring, or the like, is provided for this attachment means on a plurality of condenser bodies, and any one closure apparatus is to be fitted to any one of a number of such condenser bodies. 30

In most cases the weight of the cover 15, in cooperation with the attachment and pivoting elements described, will be sufficient to hold this cover firmly against the edges of the mouth of the condenser, and to withstand any pressure of 35 molten metal which may press against the bottom of it. In the event that this is not sufficient to keep the cover firmly pressed against the mouth at all times, a clip or catch, not shown, may extend from the top of the band 11 and 40 engage the top of the cover 15 and press down upon it when it is in a closed position, cooperating with the arms 22 and 22' to hold the cover firmly. Such a catch may be disengaged by having it pivotally connected to the band 11 and 45 movable in a horizontal plane to disengage the cover 15 and permit it to be raised when desired.

A modified form of cover is shown in Fig. 5, the body of the cover being represented by 15', but with otherwise substantially the same pivotal 50 means arrangement as hereinbefore discussed. With this modification, there is a substantially flat portion 25, so formed that with this cover over the mouth of the condenser there is a space left between the top of the cover and the inner 55 top of the mouth, thus permitting gases to escape from the condenser. This form of cover can conveniently be formed of a metal piece, such as iron, faced on the inside with a suitable thermal insulating layer, or of an iron frame over 60 which is molded a ceramic cover, as previously discussed.

A minor portion of the zinc originally present in the ore often escapes from the condenser along with effluent gases, generally in the form of fine, 65 suspended particles of zinc oxide and/or zinc. Most of this valuable material, which in many cases is lost, may be recovered by attaching to the cover a small vessel provided with baffles, or filled with coarse absorbent material such as coke 70 or charcoal or even with electrical precipitators, which collect this suspended material and from which it may be readily recovered.

It will, of course, be appreciated that other attachment means than the band 11 may be used, 75

and still fulfill the requirements and carry out the spirit of the invention, although one particular means will not necessarily be the equivalent of another, and all such modifications should be provided with suitable pivotal means, to which the arms 22 and 22' may be attached, and with the limitations discussed. Thus, as one other example, a yoke with projecting pivotal means may be molded in the body of the condenser.

10 10 What I claim is:

1. A closure for the mouth of an elongated horizontal vessel, which comprises in combination attachment means to secure the closure to the body of said vessel, a cover for the mouth 15 of said vessel adapted to retain a liquid material and to pass gases and vapors, an arm pivotally attached to each side of said cover at points on a horizontal line passing between the center and top of said cover, each said arm being pivotally attached to said attachment means at points 20 on a horizontal line and relatively higher than the first said horizontal line.

2. In a closure for a horizontal elongated vessel having a mouth at one end which is substantially 25 in a vertical plane, the combination which comprises a cover for said mouth adapted to fit closely at the bottom thereof to retain liquid material and adapted to permit gases and vapors to escape from the top thereof, attachment means 30 secured to the body of said vessel, pivotal means on either side of said cover having a common horizontal axis, said axis being between the top of said cover and its center of gravity, pivotal means on either side of said attachment means 35 having a common horizontal axis, the axis of the second said pivotal means being substantially above the first said pivotal means when said cover is closed, and arms joining said attachment means and said cover.

40 3. A closure combination, which comprises an elongated, substantially horizontal vessel having a mouth at one end, a cover for said mouth adapted to retain a molten metal in said vessel and to pass gases and vapors from said vessel, attachment means secured to said vessel near the mouth end, an arm attached thereto at one end pivotally connected to each side of said cover and between the center of gravity and the top of said cover, the other end of each said arm 45 being pivotally connected to said attachment means and at points substantially higher than said connections to the cover when in a closed position, the said arms having a length sufficient to hold said cover firmly against said mouth when 50 closed.

55 4. In a zinc condenser, the combination com-

prising a substantially horizontal condenser body, attachments means secured to said condenser body, an arm on either side of said condenser body and pivotally attached to said attachment means on a horizontal axis appreciably above the center of said condenser body, a cover for the mouth of said condenser body adapted to fit firmly against said mouth at the bottom portion thereof and to permit gases to escape from the upper portion thereof, the said arms being pivotally attached to said cover on a horizontal axis between the center and top thereof, the said horizontal axis on said cover being substantially lower than the said horizontal axis on said attachment means when said cover is closed. 1

5. A closure for the mouth of a vessel which is substantially in a vertical plane, which comprises a cover comprising thermal insulating material, a pivotal means located on each side of said cover each complementary to the other and located on a line substantially above the center of gravity of said cover, a vent hole located in the top part of said cover, attachment means for attaching said closure to said vessel, pivotal means on said attachment means located on each side of said vessel, each complementary to the other and located so as to be positioned substantially higher than the corresponding pivotal means on said cover when closed, and an arm joining each pivotal means on said attachment means with the corresponding pivotal means on said cover. 2

6. A closure for the mouth of an elongated horizontal vessel, which comprises in combination a cover for the mouth of said vessel adapted to retain a liquid material, an arm pivotally attached to each side of said cover at points on a substantially horizontal line passing between the center and top of said cover, each said arm being pivotally attached to said vessel at points substantially on a horizontal line and relatively higher than the first said horizontal line. 3

7. A closure combination, which comprises a substantially horizontal vessel having a mouth substantially in a vertical plane, a cover for said mouth comprising thermal insulating material and adapted to retain a liquid material, means for releasing gases and vapors from said combination, an arm pivotally attached to each side of said cover at points on a substantially horizontal line passing between the center and top of said cover, each said arm being pivotally attached to said vessel at points substantially on a horizontal line and relatively higher than the first said horizontal line. 4

FOREST C. BARBER.
